SIMULATED LACE ARTICLE

Application filed October 31, 1930. Serial No. 492,488.

This invention relates to a lace-like article of manufacture and more particularly to a product realistically simulating the appearance of genuine lace or other needlework articles.

An object of the invention is to produce a simulated lace having the characteristic appearance of genuine lace.

Another object is the production of various articles formed of such simulated lace.

A further object is the production of a simulated lace and articles made therefrom having the appearance of real lace, by a method which may be easily and economically carried out.

Yet another object is the production of a simulated lace which is grease-proof and moisture-proof, which is well adapted to resist penetration of moisture or grease from wet or greasy articles placed thereon, and the cost of which is so small that it can be thrown away after being once used.

Other objects of the invention will in part be obvious and will in part appear herein-after.

The invention accordingly comprises a product possessing the features, properties, and the relation of components which will be exemplified in the product hereinafter described and the scope of the application of which will be indicated in the claims.

For a fuller understanding of the nature and objects of the invention, reference should be had to the following detailed description taken in connection with the accompanying drawings, in which;

Fig. 1 is a view of one embodiment of the invention showing a doily or center-piece made in accordance with the principles there-of; and

Fig. 2 is a view of such lace made in strip form.

Hitherto lace-like articles such as doilies have been made in various ways, as for example by the stamping of perforated and/or embossed patterns from paper. Such imitations are quite unlike genuine lace in appearance and are not amenable to the use of delicate patterns, difficulty being experienced in the stamping of fine threads and small open-

ings or interstices. Also, being perforate and being made of pervious paper, such articles cannot resist the penetration of grease or moisture that is possible with the product about to be described.

In accordance with the present invention, simulated lace is formed by imposing an opaque, or substantially opaque lace pattern on a sheet of transparent material, preferably a sheet made of regenerated cellulose, sometimes known as transparent cellulose paper. This material, because of its transparency and its imperviousness to moisture, grease and the like, is admirably suited for use as a ground material on which to print lace patterns.

A preferred method of forming the design on the transparent ground material is by printing. The plate for printing the lace pattern is preferably obtained by making a photo-engraving of actual lace, although other methods of forming and applying the design are contemplated within the scope of this invention. By utilizing this preferred method, authentic reproductions of any desired pattern of lace can be made. Thus it is possible to manufacture cheaply for general use copies of rare and valuable old laces, modern patterns and, in short, any type of lace that may be desired. The lace may be printed in white or in any color or combination of colors.

Referring more particularly to the drawings and especially to Fig. 1, there is shown a simulated lace-like article made in the manner described above and in the form of a doily or center-piece, comprising a transparent ground material 10, having a lace design generally designated at 11, disposed thereon. This article is an actual lace pattern and, because of the transparency of the interstices in the pattern, has the appearance of the real lace from which it is copied. This close resemblance to real lace is especially marked when the doily or other article is placed against a dark or contrasting background, such as a table top. The pattern may be extremely fine and delicate if desired, since threads, which are printed, and the interstices, which comprise the unprinted por-

tions of the transparent ground material, may be made quite small. Such articles can be effectively used as a table cover, bureau cover and the like, especially when placed under glass; and because of its imperforate structure and inherent imperviousness, is also admirably fitted for use as a doily upon which wet or greasy glasses, dishes and the like may be placed without harm to the underlying furniture. As illustrated, the transparent ground material is trimmed so that the edges thereof approximate or, if desired, closely follow the bounding edges of the lace design. Due to the transparency of the cellulose sheet, perfect accuracy in trimming the sheet to the boundary edges of the design is not necessary, since the transparent sheet is practically invisible when placed upon a table. This avoids the necessity of preparing expensive trimming dies and for registering the dies with great accuracy with the printing on the sheet. In practice, as stated above, the ground material is trimmed so that its edges approximate but do not follow in all detail the bounding edges of the lace design, leaving a transparent margin which is not noticeable in use.

Fig. 2 illustrates another adaptation wherein the simulated lace is made in the form of a strip, it being generally useful in this form as a lace edging.

It will be seen that this invention provides a simulated lace having the actual appearance of genuine lace, but which is comparatively cheap and subject to widespread use. An important aspect of the invention resides in the ability to make generally available rare and historic old patterns, the present enjoyment of which is necessarily limited.

Since certain changes may be made in the above article of manufacture and different embodiments of the invention could be made without departing from its scope, it is intended that all matter contained in the above description shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. A simulated lace-like article capable of use as a table covering or the like, comprising a flexible transparent ground sheet and a relatively opaque lace-like design printed thereon.

2. A simulated lace-like article capable of use as a table covering or the like, comprising a flexible transparent ground sheet of moisture and grease-proof cellulosic material and

a relatively opaque lace-like design printed thereon.

3. A simulated lace-like article capable of use as a table covering or the like, comprising an imperforate transparent flexible sheet having printed thereon in relatively opaque ink a design simulating an actual piece of decorative lace, the transparency of the sheet giving to the interstices of the design the appearance of openings through the lace. 70

4. A simulated lace-like article capable of use as a table covering or the like comprising an imperforate transparent flexible sheet having printed thereon in relatively opaque ink a design simulating an actual piece of decorative lace, the sheet being trimmed to approximate but not to follow in all detail the bounding edges of the lace design, the transparency of the sheet rendering the interstices of the design and the marginal portions of the sheet beyond the bounding edges of the design substantially invisible when in use, the interstices of the design having the appearance of openings through the lace and the apparent boundary of the article being the bounding edges of 90 the lace design. 80

5. A method of making a simulated lace-like article capable of use as a table covering or the like which comprises preparing a photographic reproduction of lace, preparing a printing plate from said photograph, and printing from said printing plate upon a sheet of transparent flexible material in relatively opaque ink. 95

In testimony whereof I affix my signature. 100
